United States Patent Office

Des. 216,171
Patented Nov. 25, 1969

216,171

CONTAINER WITH SLIDING COVER

Theodore C. Murr, 2001 Wentworth Ave.,
South St. Paul, Minn. 55118

Filed Apr. 28, 1967, Ser. No. 6,880

Term of patent 14 years

Int. Cl. D3—99

U.S. Cl. D67—1

FIG. 1.

FIG. 4.

FIG. 5.

FIG. 2.

FIG. 3.

FIG. 1 is a rear elevational view of a container with sliding cover showing my new design;

FIG. 2 is a top plan view taken from the direction of the handle, as shown in FIG. 1;

FIG. 3 is a bottom plan view;

FIG. 4 is a side elevational view; and

FIG. 5 is a front elevational view.

I claim:

The ornamental design for a container with sliding cover, as shown.
